US00D855189S

(12) **United States Design Patent** (10) **Patent No.:** **US D855,189 S**
(45) **Date of Patent:** **** Jul. 30, 2019**

(54) **PATIENT TABLE**

(71) Applicant: **Siemens Healthcare GmbH**, Erlangen (DE)

(72) Inventors: **Bruno Doerrfuss**, Neunkirchen (DE); **Florian Hilbig**, Munich (DE); **Daniel Lerch**, Weilersbach (DE); **Selma Osmanlie**, Forchheim (DE); **Lei Pan**, Shanghai (CN); **Carsten Thierfelder**, Pinzberg (DE)

(73) Assignee: **Siemens Healthcare GmbH**, Erlangen (DE)

(**) Term: **15 Years**

(21) Appl. No.: **29/595,288**

(22) Filed: **Feb. 27, 2017**

(30) **Foreign Application Priority Data**

Aug. 30, 2016 (EM) 001452148

(51) **LOC (11) Cl.** **24-02**

(52) **U.S. Cl.**

USPC **D24/183**

(57) **CLAIM**

The ornamental design for a patient table, as shown and described.

DESCRIPTION

FIG. 1 is a front elevational view of a patient table showing our new design;

FIG. 2 is a back elevational view thereof;

FIG. 3 is a top plan view thereof;

FIG. 4 is a bottom plan view thereof;

FIG. 5 is a side elevational view of the right side thereof;

FIG. 6 is a side elevational view of the left side thereof; and

FIG. 7 is a perspective view taken generally from the top, front, right-hand side thereof; and,

FIG. 8 is a perspective view taken generally from the top, back, right-hand side thereof.

The broken lines are included for the purpose of illustrating portions of the patient table that form no part of the claimed design.

1 Claim, 8 Drawing Sheets
